UNITED STATES PATENT OFFICE.

LEOPOLD HAUSER, OF NEW YORK, N. Y., ASSIGNOR OF ONE-HALF TO SIMON WEIL, OF NEW YORK, N. Y.

FOLDING NECKTIE-HOLDER.

1,112,611.

Specification of Letters Patent.

Patented Oct. 6, 1914.

Application filed September 17, 1918. Serial No. 790,227.

To all whom it may concern:

Be it known that I, LEOPOLD HAUSER, a citizen of the United States, and a resident of the borough of Manhattan of the city of New York, in the county and State of New York, have invented certain new and useful Improvements in Folding Necktie-Holders, of which the following is a specification.

The invention relates to necktie holders and one of the objects is to produce a neat and attractive tie holder in which the ties can be kept in tidy arrangement when the holder is in extended or unfolded position and which can be readily folded and yet retain the ties in good condition when the holder is placed in a traveler's grip or other receptacle.

The tie holder which is the subject of this invention is particularly useful for tourists or other traveling men.

As showing a specific embodiment of the invention reference is made to the drawings forming a part of this specification.

In said drawings Figure 1 represents one form of tie holder in its unfolded or extended position. Fig. 2 is a view of the same holder in its folded or closed position. Fig. 3 is a longitudinal sectional view taken on the line 3—3 of Fig. 1 looking in the direction of the arrows. Fig. 4 is a transverse sectional view taken on the line 4—4 of Fig. 1 looking in the direction of the arrows. Fig. 5 is a transverse sectional view taken on the line 5—5 of Fig. 1 looking in the direction of the arrows. Fig. 6 illustrates another form of holder in its extended or unfolded position. Fig. 7 illustrates the same holder in its folded or closed position. Fig. 8 is a longitudinal sectional view taken on the line 8—8 of Fig. 6 looking in the direction of the arrows. Fig. 9 is a transverse sectional view taken on the line 9—9 of Fig. 6, looking in the direction of the arrows.

In both forms of the invention which is shown in the drawings the tie holder comprises a main member. This main member is designated as A in Fig. 1 and as B in Fig. 6. Each of these main members comprises a back or body portion, an under flap or lower portion and an upper flap or top portion.

In the form of holder illustrated in Figs. 1 to 5 inclusive the back or body portion is designated by C, the under flap or lower por-

tion by D, and the upper flap or top portion by E. In the form illustrated in Figs. 6 to 9 the back or body portion is designated by F, the under flap or lower portion by G, and the upper flap or top portion by H.

In each form a metallic tie-supporting bar, 60 rod or loop K is connected by means of the hinge members L to the upper part of the back or body portion of the tie holder. It will be observed from an inspection of the drawings that this supporting bar K extends 65 transversely of the tie holder and that it is located on the inner side of the back.

The upper flap in each form of holder is provided with a pocket or receptacle M that is located on the inner side of said flap. 70 This pocket or receptacle has a small flap or cover m, the free end of which is secured in place by the clasp or clip n.

In the form shown in Figs. 1 to 5 inclusive there is a pair of overlapping inner flaps N 75 and O which are detachably secured together at their free ends by the clasps or clips o. The outer edges of these overlapping inner flaps are secured to the lower flap near the side edges thereof, as is indicated at a and b. Between these overlapping inner flaps N and O on the one hand and the lower flap D on the other there is provided a space P for receiving the free ends of the ties which are strung over the 85 supporting bar K. The upper flap and the under flap are each provided with co-operating catch or clip members which are designated respectively as d and e. These serve as means for detachably securing the upper 90 flap to the under flap when the flaps occupy a folded position. The member e is also provided with an opening f for receiving a hook or other member upon which the holder 95 is hung when being used in its unfolded position.

From what has preceded, and also from an inspection of the drawings, it will be observed that the catch member on the upper flap has two ears and that one of these ears 100 is located on the outside of the flap and the other on the inside of the flap. It will also be noted that each of these ears is provided with the opening which receives a member or hook upon which the holder is hung.

When the ties are in place on the supporting bar K and the holder is hung in place in its extended position in a room the free

ends of the ties preferably remain outside of the inner flaps *n* and *o*. The free ends of the ties are inserted in the receiving space *P* under the overlapping flaps *n* and *o* when it is desired to fold the holder. In the form shown in Figs. 1 to 5 the under flap and also the body are provided with coöperating clasp or catch members *g* and *h* which serve as means for detachably securing the edge portions of the back and under flap together thus causing the folded holder to have a neat and attractive appearance to a person looking toward the edge portion, and this is because the edges of the back and under flap are held very close to each other.

In the form shown in Figs. 6 to 9 the inner flaps, instead of being secured to the under flap or lower member, are secured along the edge portions of the back or body member. These flaps are designated by the letters *Q* and *R* and are secured to the edge portions along the lines designated by *q* and *r*. The binding strap or loop comprising the members *S* and *T* is secured at *s* and *t* to the lower part of the body portion. The free ends of the members *S* and *T* are provided with clips or catches *u* that serve as means for detachably securing said ends together. The function of this strap is to hold the ties against the back prior to their free ends being folded back upon the tie portions that are adjacent to the supporting rod *K*, whereby the inner flaps *Q* and *R* can be brought into position to cover the free ends which have thus been folded back upon the rest of the ties. When the holder is being used merely as a support for the ties when hanging in the room, these inner flaps *Q* and *R* are secured together back of the ties which hang freely outside of the same. In this form the clip or catch members *d* and *e* are the same in their construction as the corresponding members shown in the holder illustrated in Figs. 1 to 5.

In both forms of holder it will be noted that the upper flap or top portion, the back or body portion and the under flap or lower portion are each respectively provided with stiffening members *V*, *W* and *X* which are located between the lining *Y* and the outer covering member *Z*. Both the lining *Y* and the outer member *Z* are continuous strips of material which extend the full length of the holder and the outer member and the lining serve as means to flexibly connect at *w* the top portion to the body portion and at *z* the bottom portion to the body portion. The lining and the receptacle *M* are preferably formed of some fancy fabric, while the outer portion of the holder is preferably formed from a strip of leather. In the form shown in Figs. 1 to 5 the inner flaps may be formed of the same material as the lining, while in the form shown in Figs. 6 to 9 it is preferable to form the inner flaps of the same ma-

terial as the outer portion of the holder. The inner flaps are provided with stiffening members such as *n* *n* in Fig. 5 and *q* *q* in Fig. 9 in order that the shape of these inner flaps will be maintained when the holder is subjected to use.

It is obvious that various forms and modifications may be made without departing from the spirit and scope of the invention.

What I claim is:

1. A necktie holder comprising a main member having a back, an upper flap and an under flap, each of which flaps are connected to the back so that they can be moved from an extended or unfolded position to a folded position over the back, the holder having at the upper portion of the back a transversely extending rod for supporting the ties, the lower flap having thereupon overlapping inner flaps which provide between them on the one hand and the lower flap on the other a space for receiving the free ends of the ties when strung over the supporting rod.

2. A necktie holder comprising a main member having a body portion, an upper flap portion and an under flap portion, means for detachably securing the flaps together, a metallic tie supporting loop having a hinged connection to the back and inner flaps for receiving thereunder a portion of the ties when strung over the supporting loop, said inner flaps being hinged near the longitudinal side edges of a portion of the main member.

3. A necktie holder having a continuous strip of material which provides the outer portion of a main member comprising a back or body portion, an upper flap and an under flap, the holder also having a stiff tie supporting loop secured to the upper part of the body portion, a pair of inner flaps secured to the lower flap adjacent to the side edges thereof, and means for catching or detachably securing the side portions of the lower flap to the side portions of the body portion.

4. A necktie holder comprising a back, an upper flap and an under flap, a transversely extending tie supporting bar which is secured to the upper portion of the back, means for catching or detachably securing the top flap in place over and upon the under flap, means for catching or securing the side portions of the under flap to the side portions of the back, and overlapping inner flaps for receiving thereunder portions of the ties which have been placed on the supporting bar, the upper flap being provided with an opening for receiving a member upon which the holder may be hung, each of the flaps and also the back being provided with a stiffening member that is located between the lining of the holder and a strip that is continuous from the top flap

to the lower flap and which strip serves as the outer portions of the upper flap, the body and the under flap.

5. A folding necktie holder having a back, an under flap, an upper flap and a lock or catch for detachably securing the upper flap to the under flap, the lock or catch member which is on the upper flap having ears that are located one on the outside of the flap and one on the inside of the flap and each

ear being provided with an opening for receiving a member or hook upon which the holder may be hung.

This specification signed and witnessed this 12th day of September, A. D. 1913.

LEOPOLD HAUSER.

Signed in the presence of—

EDWIN A. PACKARD,
G. MCGRANN.
